UNITED STATES PATENT OFFICE.

WALTHER SCHMIED, OF GENEVA, SWITZERLAND

INTERNAL-COMBUSTION ENGINE.

1,141,658.

Specification of Letters Patent.

Patented June 1, 1915.

Application filed November 2, 1910. Serial No. 590,310.

To all whom it may concern:

Be it known that I, WALTHER SCHMIED, citizen of Switzerland, residing at Avenue de la Servette 9, Geneva, in the Confederation of Switzerland, have invented certain new and useful Improvements in Internal-Combustion Engines, of which the following is a specification.

The present invention relates to a device which, during the exhaust stroke and also for the next following suction stroke, lengthens automatically the stroke of the working piston of four stroke combustion engines by means of an eccentric disk or a small crank which is arranged in one of the two cross-head ends of the connecting rod, in such a manner that in the dead center position of the piston movement at the end of the exhaust stroke the working piston is led up to the cylinder head while at the compression stroke which follows, this lengthening of the stroke does not take place, so that the stroke as well during this compression stroke as during the following expansion stroke maintains its normal length and leaves a free space between the working piston and the cylinder head, which space forms the compression chamber and in which space the admitted gas charge is compressed. The object of the present invention is to push out of the cylinder by the exhaust stroke of the working piston all of the combustion gases, in order that the admission of the new charge may take place without clearance or prejudicial space which would reduce the volume efficiency of the suction stroke.

Another object of the invention is to considerably increase the volume of the gas drawn or sucked in with regard to ordinary motors by the fact that the exhaust stroke and therewith the suction stroke automatically increases to an amount corresponding to the length of the compression chamber of the cylinder. Moreover the gas or gases drawn or sucked in are not heated or contaminated by burnt gases remaining in the cylinder. This allows a higher compression to be obtained and greatly facilitates the ignition of the gas mixture, whereby the efficiency of the motor is increased and a better utilization of the fuel secured.

In the annexed drawing, several forms of the invention are shown.

Figures 1 to 7 show a constructional form

in which the eccentric disk is arranged in the cross-head of the connecting rod at the crank pin. These figures show also the different positions of this eccentric during the working of the motor, the working piston and the cylinder of the motor being shown diagrammatically.

In the Figs. 1 to 7, *a* designates a cylinder of a motor represented diagrammatically by a line, and *b* the working piston, being shown in section, *c* designates the piston pin, that is the pin which connects the connecting rod and the working piston, *d* the connecting rod, *e* the eccentric which is pivoted in the cross-head of the connecting rod *d*. The eccentricity of the eccentric disk *e* is equal to about the half length of the compression chamber of the cylinder *a* of the motor. By the term compression chamber, as herein employed, I mean that portion of the cylinder between the head thereof and the face of the piston when in its dead center position at the normal stroke, as shown in Fig. 7, this compression chamber extending between the line *x* and the line *y*, as indicated in Fig. 7. The eccentric *e* is mounted freely on the crank pin *f* of the crank *f* and further freely rotates in the head of the connecting rod *d*. The energy of the piston *b* is transmitted by the crank *f* to the main shaft *g* of the motor.

The device works as follows:—As long as the pressure in the motor-cylinder at the working side is not very different from the atmospheric pressure—for example—during the exhaust—and the suction strokes of the piston, the eccentric *e* takes, under the action of the centrifugal force, the position shown in Figs. 1 to 5. The centrifugal force tends to move the center *e*² of the eccentric disk as far as possible from the center of the circle described by the crank pin, or from the axle of the driving shaft *g*, so that the center *e*² of the eccentric tends to travel outside the crank circle but concentric to it in a new circle, the diameter of which is greater than that of the said crank cycle by twice the eccentricity of the eccentric *e*. But thereby the stroke of the working piston is also increased by the same amount and as the eccentricity is equal to the half length of the compression chamber as hereinbefore explained, the working piston travels through the whole length of this chamber, until it reaches the head of the cyl-

inder and all burnt gases are expelled out of the cylinder a , (Fig. 3).

During the first half of the exhaust stroke during which the movement of the piston is accelerated, the inertia of the piston b acts in opposition to the centrifugal force, so that the eccentric disk is forced to take a position which corresponds to the direction of the resultant of the centrifugal force and of the piston reaction. But in the middle of the stroke the latter becomes equal to zero, so that the centrifugal force acts alone and gives to the eccentric e a radial outwardly directed position, Fig. 1. In the next half of this stroke, the speed of the piston becoming again slower, the inertia of the piston acts again and produces, instead of a retardation of the movement of the center of the eccentric e , like in the first half-stroke, a certain advance of the movement of the same, Fig. 2. In the dead center position, Fig. 3, at the end of the exhaust stroke, this advance however is again equal to zero, the piston inertia and the centrifugal force having the same direction. The now following suction stroke of the working piston begins directly at the cylinder head, without any clearance or prejudicial space resulting from the existence of an ordinary compression chamber. Owing to the piston reactions, the motion of the eccentric center e^2 is retarded with regard to the crank pin during the first half of this stroke, Fig. 4, and is in advance during the second half stroke, and is again placed radially and outwardly when the following dead center position is reached, at the end of the suction stroke, Fig. 5, the eccentric rotating continuously in the cross-head end of the connecting rod. During the following compression stroke, the pressure in the cylinder a rises very rapidly to several atmospheres. The working piston b exerts therefore upon the connecting rod d a strong pressure which is transmitted by the rod to the eccentric e and forces the latter continuously to take such a position that the distance between the crank pin f' and the piston pin c remains a minimum, which happens when the center e^2 of the eccentric is in line with the longitudinal axis of the connecting rod, which axis passes through the center of the piston pin c and the crank pin f' , Figs. 5, 6 and 7. The eccentric e therefore does not change its position with regard to the cross-head of the connecting rod, as the centrifugal force and the piston accelerating forces are too small to be able to balance the overpressure produced by the compression in the interior of the cylinder. The stroke of the working piston b is therefore only of a length which is equal to the crank circle diameter, so that the piston when reaching the upper dead center position, has only traveled through a part of the cylinder length and there remains consequently a

space or chamber between the piston face and the cylinder head, which chamber contains the compressed gas charge, Fig. 7. Also during the expansion stroke which follows the combustion, the eccentric e , owing to the overpressure resulting from the pressure in the cylinder, cannot change its position with regard to the connecting rod, so that when reaching the following lower dead center position, the parts are in the positions shown in Fig. 5. But now the exhaust valve has been opened, so that the pressure in the cylinder has become lower. During the following exhaust stroke the centrifugal force and the reactions of the piston can again operate the eccentric and place the same radially outwardly, whereby the stroke of the piston b is increased as shown, and whereafter the whole described cycle of operations is repeated. It will be understood that the crank turns in a clockwise direction.

In order to obtain a smooth running of the motor without vibrations, a rigidly fixed counterweight may act in a well known way on the crank shaft opposite to the eccentric disk. But as the eccentric disk e is sometimes less, sometimes more distant from the driving shaft g , its centrifugal force will be counterbalanced only at times by a counterweight fixed on the crank shaft. To avoid this, even also the eccentric disk e may be provided with a counterweight e' , such as is represented in Fig. 1; so that the center of gravity of the combined eccentric and its counterweight, will always assume the same position and will remain in the middle of the crank pin f' . The centrifugal force of the combined eccentric and its counterweight, will now be invariable and may be completely counterbalanced by a rigid counterweight fixed on the crank shaft opposite to the eccentric disk. Notwithstanding the fact that centrifugal force also acts at the lower part of the connecting rod d , the action of the eccentric disk will be certain, because this action is by the inertia of the piston during the period of retardation in both the exhaust and suction strokes of the piston. If there are several connecting rods of a multi-cylinder motor connected to the crank pin, each connecting rod is provided with its own separate eccentric e . For the purpose of rendering more easy the assembling or fitting up of the machine, the eccentric may be made of several pieces connected together by means of screws or in any other suitable manner.

I claim as my invention:

1. In a four cycle internal combustion engine, and in combination, a cylinder, a piston, a connecting rod secured at one end to the piston, a crank, a crank pin, and an eccentric on the crank pin and to which the opposite end of the connecting rod is se-

cured, the said eccentric being loosely mounted on the said crank pin and unassociated with any mechanical parts, except the connecting rod and crank pin, so that by the 5 action of centrifugal force it automatically changes its position in the operation of the engine to lengthen the piston travel during the exhaust and suction strokes, and to shorten the piston travel to its normal length 10 during the compression and expansion strokes, the latter action being effected by the pressure exerted against the piston during these last named strokes.

2. In a four cycle internal combustion engine, and in combination, a cylinder, a piston, a connecting rod secured at one end to the piston, a crank, a crank pin, and an eccentric on the crank pin and to which the opposite end of the connecting rod is secured, and a counter-weight connected to the 15 20

said eccentric, the said eccentric being loosely mounted on the said crank pin and unassociated with any mechanical parts, except the connecting rod and crank pin, so that by the action of centrifugal force it automatically changes its position in the operation of the engine to lengthen the piston travel during the exhaust and suction strokes, and to shorten the piston travel to its normal length during the compression and expansion strokes, the latter action being effected by the pressure exerted against the piston during these last named strokes. 25 30

In testimony whereof I affix my signature in presence of two witnesses.
